UNITED STATES PATENT OFFICE

EDWARDE EARLE STEPHENS, OF CHARLESTON, WEST VIRGINIA

DOORCHECK

Application filed August 30, 1930. Serial No. 478,965.

This invention relates to door stops or door checks and has for an object the provision of a simple and cheaply manufactured device, which when positioned for use, will permit of the rapid closing of a door throughout the major portion of its movement, and thus prevent the passage of flies and other insects, but which will effectually check the door just prior to its contact with the door frame, so that the door will be fully closed without noise or jar.

With the above and other objects in view, the invention further includes the following novel features and details of construction, to be hereinafter more fully described, illustrated in the accompanying drawings and pointed out in the appended claims.

In the drawings:—

Figure 1 is a fragmentary elevation illustrating the invention in use.

Figure 2 is a section on the line 2—2 of Figure 1.

Figure 3 is a similar view showing the door open.

Figure 4 is an enlarged vertical sectional view through the door check or retarder.

Figure 5 is an elevation partly in section showing a slightly different form of the invention.

Figure 6 is a vertical sectional view of another form.

Referring to the drawings in detail where-in like characters of reference denote corresponding parts, the invention is shown as applied to a screen door 10, the frame of which is indicated at 11. While the invention is shown in connection with a screen door, obviously it may be applied to other doors, or to other hinged closures.

The reference character 12 indicates a cup-like receptacle or holder which is designed for attachment to the door frame 11, and for this purpose is provided with openings for the passage of screws 13, or equivalent fastening devices. Extending from the outer edge of the receptacle 12 is an inflatable member 14. This member is formed of rubber of a suitable thickness and is arranged in the path of an arm 15. This arm is rigid and is secured to the door as shown at 16

and its free end is provided with a ball or knob 17 to engage the inflatable member 14.

When the door is moved to a closed position under the action of the spring 18, it will quickly close so as to prevent the passage of flies and other insects through the doorway. The arm 15 and the inflatable member 14 are so positioned that the ball at the end of the arm 15 will engage the inflatable member 14 just prior to contact of the door with the door frame. Closing movement of the door may thus be checked or retarded at this point, and as the remaining movement of the door will be retarded by the member 14, the door will jointly engage the frame and eliminate noise and jar.

The member 14 is provided with an air escape opening 19 which is controlled by a valve member 20 and this member is weighted as shown at 21. That portion of the member 14 within the receptacle 12 is reinforced and stiffened, and for this purpose, the form of the invention shown in Figure 4 is provided with a cup-like reinforcing member 22. This member is preferably formed of relatively heavy rubber and is vulcanized or otherwise secured to the member 14. The member 22 is provided with an opening 23 for the passage of a screw or bolt 24 which engages a nut 25 embedded between the member 14 and the member 22. The head of the screw or bolt 24 is positioned within a socket 26 provided in the receptacle.

In the form of the invention shown in Figure 6, the construction is substantially the same except that the member 14' is thickened as shown at 27, and a screw 28 is threadedly engaged with this thickened portion.

In Figure 5, the receptacle 12' is provided around its edge with an inwardly extending flange 30 which detachably engages an annular shoulder 31 provided upon an inflatable member 32.

The invention is susceptible of various changes in its form, proportions and minor details of construction and the right is here-in reserved to make such changes as properly fall within the scope of the appended claims.

Having described the invention what is claimed is:—

1. A door check including a cup-like receptacle adapted to be secured to the door frame and having an inwardly projecting socket formed centrally of the bottom thereof, a hollow inflatable member having a reinforced portion partly received by the receptacle, and a headed bolt passed through said socket and secured to said reinforced portion of the inflatable member to hold the latter associated with the receptacle.
- 5 2. A door check including a cup-like receptacle adapted to be secured to the door frame, a hollow inflatable member having a reinforced portion received by the receptacle, and means including said reinforced portion of said member for connecting the latter to the bottom of the receptacle.
- 10 3. A door check including a cup-like receptacle adapted to be secured to the door frame, a hollow inflatable member partly received by the receptacle, a cup-like reinforcing member arranged within the receptacle and vulcanized to the adjacent portion of the inflatable member, and means including said reinforcing member for connecting the inflatable member to the bottom of the receptacle.
- 15 4. A door check including a cup-like receptacle having an inwardly projecting socket formed centrally of the bottom thereof, a hollow inflatable member partly received by the receptacle, a cup-like rubber reinforcing member arranged within the receptacle and vulcanized to the adjacent portion of the inflatable member, and a headed bolt passed through the socket and threadedly connected with the reinforcing member.

In testimony whereof I affix my signature.
EDWARDE EARLE STEPHENS.
